J. REYNOLDS.
Finishing Soft Rubber Articles.

No. 16,215.

Patented Dec. 9, 1856.

UNITED STATES PATENT OFFICE.

JAMES REYNOLDS, OF NEW YORK, N. Y.

MODE OF MAKING GUTTA-PERCHA CORD.

Specification of Letters Patent No. 16,215, dated December 9, 1856.

To all whom it may concern:

Be it known that I, JAMES REYNOLDS, of the city, county, and State of New York, have invented a new and Improved Process 5 of Finishing Gutta-Percha Cords; and I do hereby declare that the following is a full, clear, and exact description of the same, reference being had to the accompanying drawings, forming part of this specification, in 10 which—

Figure 1, is a vertical central section of the machine and Fig. 2, a front view of the die and rollers.

Similar letters of reference indicate corresponding parts in both figures.

This invention consists in a novel process of finishing gutta percha cord, by means of dies and grooved rollers arranged and operating together as herein described, said dies 20 being of somewhat larger diameter than the grooves in the rollers and the cord having a windlass action feed given it by the rollers, all as herein and for the purposes set forth.

To enable others to make and use my invention, I will proceed to describe it with reference to the drawing.

A, is a bedplate supporting two standards B, B, which contain the bearings for the pair of horizontal grooved rollers C, C'. 30 These rollers have several sets of grooves f, f, for cord or pipe of different sizes and the upper one has its bearings a, a, fitted to the standards B, B, so as to be adjustable under the control of a screw b. They are 35 geared together to rotate at the same velocity.

E, is a standard having an opening d, whose sides are made of V form in the horizontal section of their lower parts, for the 40 purpose of holding the upright die D, D', which is made in two parts each part containing half the die. The lower part D' of the die rests upon the bottom of the opening d, on the standard E, and the upper part 45 is intended to be held down upon it by a screw e, in the top of the standard. The interior of the die is of rounded form as shown in Fig. 1. The standard E is placed as close as practicable to the rollers C, C', 50 and the die should stand nearly opposite the bottom of the lower roller C'. The standard should be provided with a number of dies, corresponding to the number of the several grooves of the rollers and should be adjustable to bring the die which is placed in it, 55 opposite to that set of grooves in the rollers

with which it is intended to work. Each die should be rather larger than the grooves with which it is intended to work. The pair of grooves forming an aperture of the intended size of the finished cord or exterior of the tubing, and the die being smaller than the cord or exterior of the tubing before it is operated upon.

The cord or tubing G to be operated upon 65 which is shown in red color in both figures, is brought to the machine in the condition in which it comes from the machine in which it has been molded. To introduce it to the machine, the screws b, d, are unscrewed and 70 one end of it is led through the die under the lower roller and between the rollers, after which, the screws b, d, are screwed down. Rotary motion is then given to the rollers by suitable means in the direction of 75 the arrows shown upon them and the cord or tubing is drawn by the bottom roller (which, by its arrangement relatively to the die, acts as a windlass) through the die, after which it passes through the rollers and 80 is conducted by an attendant over the top roller and laid on the floor or on a suitable receptacle, in a coil. By this process the cord or tubing is subjected to three distinct 85 operations, viz: 1st, it is drawn, condensed and equalized in size, by passing through the die, 2nd, it is stretched between the die and the rollers, and 3rd, it is slightly compressed between the rollers to finish it with 90 a smooth surface.

The relative sizes of the die and grooves should be such as to bring the gutta percha to what is known in the manufacture of that material as the "fixed point" which is that condition in which it will just stretch no 95 more and has the greatest density, and tenacity in which condition it is best adapted for most purposes.

This machine is principally intended for the finishing of gutta percha cord, but may 100 be used for tubing, though for finishing tubing I intend generally to employ a mandrel in connection with the die to regulate at the same time the interior size and thickness.

I do not claim as new a mere combination 105 of dies and rollers, as such, variously arranged, is common in the manufacture of metallic tubing and other articles; but

What I do claim as a new and useful improvement in the manufacture of gutta 110 percha cord is—

The process herein described of finishing

gutta percha cord, by means of the dies D D', and grooved rollers C C', arranged and operating together and on the cord as described, the said dies being of larger diameter than the grooves in the rollers and serving to close up flaws, draw and compress the cord and equalize its size, while the smaller grooves in the rollers serve to slightly compress and give a smooth finish to the cord 10 and establish or sustain the feed of the cord,

without risk of bruising, by attrition, through a windless action as specified, and, by which combined action of the dies and rollers, the cord is stretched to its "fixed point" between the dies and rollers as set forth. 15

JAMES REYNOLDS.
